UNITED STATES PATENT OFFICE.

MAX BLUM AND JACOB STEIN, OF ELIZABETHPORT, NEW JERSEY.

ROPE-CLAMP.

No. 876,138.

Specification of Letters Patent.

Patented Jan. 7, 1908.

Application filed April 3, 1906. Serial No. 309,536. Renewed June 5, 1907. Serial No. 377,363.

To all whom it may concern:

Be it known that we, MAX BLUM and JACOB STEIN, citizens of the United States, residing at Elizabethport, in the State of New Jersey, have invented, certain new and useful Improvements in Rope-Clamps; and we do hereby declare the following to be a full, clear, and exact description of the invention, such as will enable others skilled in the art to which 5 it appertains to make and use the same, reference being had to the accompanying drawings, and to letters of reference marked thereon, which form a part of this specification.

Our invention relates to a rope clamp and 15 one that is designed more particularly for the tightening of rope, such as pulley lines and clothes lines, and the invention is of a class that employs tapered jaws sliding in a cylindrical sleeve so that a greater strain on the 20 rope tightens the grip.

This invention is designed to provide an article of this kind with shoulders on the front, and to limit the movement of the gripping jaws and to form bearings for the fingers 25 to hold the jaws back, when it is desired, to let the rope slip through the jaws.

A further object is to provide these jaws with ribs on their interior surfaces for engagement with the rope.

30 The invention is illustrated in the accompanying drawings, in which

Figure 1 is a side view of the device. Fig. 2 is a top view, and Fig. 3 is a section on line 3, 3, in Fig. 1. Fig. 4 is a face view of the inside of one of the jaws.

In the drawings, the body portion 10 has the eye 11 in one end for the reception of one end of a rope 12. This body portion has, also, the bulging portions 13 ending up on the 40 front end on the cylindrical part 14. Secured in the cylindrical part are the two jaw sections 15, which are formed with the shoulders 16 on the small end to limit the backward movement of the jaws, and to provide 45 finger pieces for holding them back. These

jaws have the same interior diameter for their full length, but their exterior tapers, and have the enlarged end 17. It will thus be seen that a pull on the rope away from the body portion, will tend to grip the rope and 50 secure it. To more securely hold the said rope, we prefer to provide the interior of the jaws with a series of ribs 18, of any usual construction, these jaws gripping the end 19 of the rope and assuring no slipping. 55

Between the eye 11, and the cylindrical part 14 is arranged a ring or annular portion 20 which may be integral with the body portion. The office of this ring is to guide the rope, so that when the end 19 is pulled, even 60 although the pull is not directly in line with the axis of the jaws, then the rope will not be jammed or forced between the jaws 15 at their sides. This might easily result, if the ring was absent, as the rope would act as a 65 wedge to force itself in between the jaws, if there was a distinct side pull on the free end 19 of the rope.

Having thus described our invention, what 70 we claim is:—

A device of the kind described, comprising a body-portion having bulging side pieces, an eye on one end of the body portion and a cylindrical part on the other end, the eye forming means for attaching one end of a 75 rope, a pair of tapered jaws sliding in the cylindrical part, for grasping the end of a rope, and a ring secured to the side pieces and in line with the jaws to guide the free end of the rope and prevent the entrance of the rope between the sides of the jaws. 80

In testimony, that we claim the foregoing, we have hereunto set our hands this 28th day of March 1906.

MAX BLUM.
JACOB STEIN.
